(57) **CLAIM**

The ornamental design for a umbrella wrist strap, as shown and described.

DESCRIPTION

FIG. 1 is a top view of an umbrella wrist strap with the handle portion removed in order to show the underlying surface of the umbrella wrist strap;

FIG. 2 is a side view thereof;

FIG. 3 is a front view thereof; and,

FIG. 4 is a bottom view thereof with the handle portion removed in order to show the underlying surface of the umbrella wrist strap.

The broken lines in all drawings are included for the purpose of illustrating environmental subject matter and form no part of the claimed design.
